UNITED STATES PATENT OFFICE.

JOHN J. ENGLISH, OF NEW YORK, N. Y.

FURNACE.

Application filed May 13, 1922. Serial No. 560,650.

To all whom it may concern:

Be it known that I, JOHN J. ENGLISH, a citizen of the United States, and resident of the borough of Manhattan, in the city 5 and State of New York, have invented a new and useful Improvement in Furnaces, of which the following is a specification.

In furnaces of usual construction, the temperature reached by the fire sides of furnace 10 walls is so high that the fire bricks become soft and a small film of liquefied brick is present on the face nearest the fire. Ash, which is always present in the fuel bed, also fuses at this temperature and whenever this 15 fuse ash or clinker comes in contact with the molten brick surfaces, a weld takes place. Once this weld has started, it spreads rapidly, the layer thickens and a rapid deterioration of the fire bricks takes place. 20 As this layer of clinker thickens, it chokes the fire and in the case of stoker furnaces, presents a danger of stoker destruction. Furthermore, the burning through of the walls in many instances brings about the 25 collapse of the walls with the possibility of serious as well as costly damage. This formation of clinker necessitates frequent removal to prevent it from becoming a menace. To remove the clinker, the fire 30 must be burned down and the coal on the grate is wasted. There is consequently a service loss, the loss of investment, the cost of labor for removing the clinker and the strain on the furnace side walls, because of 35 the shocks from the sledge hammers used in removing the clinker. Also the cooling of the walls requires more coal to bring them back to normal temperature and the contraction and expansion, due to this frequent 40 cooling and heating, injures the walls.

This clinker forms at certain critical points on the side walls where the fuel bed temperature is high and clinker abundance at a maximum.

45 My invention provides means for preventing this clinker formation, by the introduction of rotary side wall members at the critical points, whereby the constant changing of the side wall surfaces at these points 50 eliminates entirely the formation of clinkers, thus materially increasing the efficiency of the furnace.

55 My invention is particularly well adapted for use in connection with stoker furnaces, therefore I have represented my invention

as applied to an underfeed stoker furnace of usual type.

Practical embodiments of my invention are represented in the accompanying drawings, in which

60

Fig. 1 represents a detail longitudinal vertical section through the furnace, taken in the plane of the line I—I, of Fig. 3; looking in the direction of the arrows; certain of the parts being shown in full lines 65 and certain of the parts in dotted lines.

Fig. 2 represents a similar detail section, taken in the plane of the line II—II of Fig. 3.

Fig. 3 represents a detail transverse vertical section taken in the plane of the line III—III, of Fig. 1, looking in the direction of the arrows.

Fig. 4 represents a back view of one form 70 of a side wall member section.

75

Fig. 5 represents an inverted end view of the same.

Fig. 6 represents a face view showing the 80 same perforated.

Fig. 7 represents a back view of another form of side wall member section.

85

Fig. 8 represents an inverted end view of the same.

Fig. 9 represents a face view showing the 85 same perforated.

Fig. 10 represents a detail section showing the means for securing the sections to their wheel.

The fixed side walls of the furnace are denoted by 1, 1, and the grate by 2. The 90 fuel hopper is denoted by 3, the fuel feeding plunger by 4 and the shaft of the fuel feeding means by 5. It will be understood that all of these parts are of well known construction.

95

Recesses 6, 6 are formed in the fixed side walls 1, 1 of the furnace at the points where there is a tendency for the clinkers to form. These recesses extend above and below the grate level, the tops of the recesses being of 100 semi-circular arched form. Wheels 7, 7 are located within the recesses 6, 6 and are carried by stub shafts 8; 8 rotatably mounted in the side walls of the furnace below the grate level. The side wall members are 105 removably secured to the wheels 7, 7 with their fire faces substantially flush with the fire faces of the fixed side walls 1, 1, so as to form a continuation of the said fire walls above the grate level. These side wall mem- 110

bers are preferably composed of annular series of sections separately secured to their respective wheels 7, 7 for purposes of replacement and renewal.

5 These side wall member sections 9, shown in Figs. 1 to 6 inclusive are of metal construction, while the sections 9* shown in Figs. 7 to 10 inclusive are of fire brick construction. These sections may be perforated 10 as shown in Figs. 6 and 9 to permit the passage of air therethrough.

The inner peripheral edges of the sections 9 are provided with lips 10 seated in the hub 11* of the wheel 7. These sections 9 are also 15 provided with laterally extending arms 11 overlapping the periphery of the wheel 7 and suitably secured thereto by fastening devices, such as bolts 12.

The inner peripheries of the sections 9* 20 are provided with lips 13 seated in the hub 11* of the wheel 7, the outer peripheries of these sections 9* being removably secured to the peripheral rim 14 of the wheel 7, by suitable fastening devices, such as bolts 15.

25 In both instances it is to be understood that these annular series of sections form a continuous wall member.

The means which I have shown for driving the rotary wheels 7, 7 and their side wall members from the fuel feeding mechanism shaft 5, is constructed, arranged and operated as follows:—

A cross shaft 16 mounted at its ends in hangers 17, 17 is provided with spur gears 18, 18 meshing with pinions 19, 19 on the inner ends of the stub shafts 8, 8. This cross shaft 16 is provided with ratchets 20, 20, engaged by pawls 21, 21, carried by arms 22, 22, loosely mounted on the cross shaft 40 16, which arms are attached to the ends 23, 23, of connecting rods 24, 24, the opposite ends of which rods are pivoted at 25, 25 to crank arms 26, 26 on the fuel feeding mechanism shaft 5. Therefore, the rotary movement 45 of the shaft 5 will impart an intermittent rotary movement to the wheels 7, 7 and their side wall members.

The driving connection is intended to be so proportioned as to give the required 50 speed of rotation to the rotary side wall members, to ensure the best results.

From the above description it will be seen that air is permitted to circulate in the recesses 6, 6 of the side walls 1, 1 back of 55 the rotary side wall members. It will also be seen that the provision of sectional rotary side wall members permits the renewal and interchanging of the said sections as required, said renewals being accomplished 60 when the sections are located in the air space below the grate level.

The circulation behind the rotary side wall members accomplishes to a great degree the decrease of radiation loss and keeps 65 the fire surfaces well below fusing point.

Furthermore, as only certain portions of these rotating side wall members are exposed to furnace temperature at any one time, excessive heating of these portions is prevented. No portions of the rotary side 70 wall members are above the grate level sufficiently long to become excessively heated, the portions below the grate level being cooled by air circulation. Therefore, cool portions of the side wall members are continually replacing the more heated ones. Where a draft space occupies the entire space beneath the grate level, all benefits 75 derived from air circulation are greatly increased and all heat absorbed by the portions of the rotary side wall members which has come from above the grate level is returned, the air which cools them absorbing the heat which is an aid to combustion for 80 which the air is used.

By mounting the rotary side wall members so that their surfaces may be substantially flush with the fixed side walls, the movement of the side wall members serves to slice the fuel bed, breaking it up and admitting more air at these points. Thus the fire becomes cleaner and the tendency to the 90 formation of clinkers greatly decreases, resulting in the tendency of the clean fire to burn off any clinker approaching the wall.

95 It will also be noted that a space below the grate is provided which is easily accessible for inspection, renewal, etc.

While I have disclosed only one of these 100 rotary side wall members in each side wall of the furnace, it is obvious that any number of these members may be inserted that may be necessary.

While I have particularly shown and explained this invention as applied to the side 105 walls of a furnace, it is obvious that it may be applied wherever desired.

It is also evident that various changes 110 may be resorted to in the construction, form and arrangement of the several parts without departing from the spirit and scope of my invention; hence I do not wish to be limited to the particular embodiments herein shown and described, but

115 What I claim is:—

1. In a furnace, a grate, vertically disposed fixed walls, wall members having their fire faces substantially flush with said fixed walls, and means for actuating the wall members to bring different parts of the fire face of each successively into and out of operative relations with respect to the 120 grate.

125 2. In a furnace, a grate, vertically disposed fixed walls, wall members extending above and below the grate level, said wall members having their fire faces substantially flush with said fixed walls, and means for actuating the wall members to bring different parts of the fire face of each successively 130

into and out of operative relations with respect to the grate.

3. In a furnace, a grate, vertically disposed fixed walls, sectional wall members having their fire faces substantially flush with said fixed walls, and means for actuating the wall members to bring different parts of the fire face of each successively into and out of operative relations with respect to the grate.

4. In a furnace, a grate, vertically disposed fixed walls, sectional wall members extending above and below the grate level, said wall members having their fire faces substantially flush with said fixed walls, and means for actuating the wall members to bring different parts of the fire face of each successively into and out of operative relations with respect to the grate.

5. In a furnace, a grate, vertically disposed fixed walls, rotatable wall members having their fire faces substantially flush with said fixed walls, and means for rotating said wall members to bring different parts of the fire face of each successively into and out of operative relations with respect to the grate.

6. In a furnace, a grate, vertically disposed fixed walls, rotatable wall members provided with series of removable sections, the fire faces of said sections being substantially flush with said fixed walls, and means for rotating the wall members to bring different parts of the fire face of each successively into and out of operative relations with respect to the grate.

7. In a furnace, a grate, vertically disposed fixed walls, rotatable wall members provided with series of removable perforated sections, the fire faces of said sec-

tions being substantially flush with said fixed walls, and means for rotating the wall members to bring different parts of the fire face of each successively into and out of operative relations with respect to the grate. 45

8. In a furnace, fixed walls, movable sectional wall members extending above and below the grate level, and means for rotating said members to bring successive sections above and below the grate level. 50

9. In a furnace, fixed walls having recesses, wheels located in said recesses, wall members carried by said wheels and forming continuations of said fixed walls, and means for rotating said wheels. 55

10. In a furnace, fixed walls having recesses, wheels located in said recesses, wall members comprising annular series of sections removably secured to said wheels and forming continuations of said fixed walls, 60 and means for rotating said wheels to bring successive sections of the wall members above and below the grate level.

11. In a furnace, a grate, fuel feeding means, vertically disposed fixed walls, and rotatable wall members driven from said fuel feeding means, to change the relations of the parts of the fire face of each member with respect to the grate. 65

12. In a furnace, a grate, fuel feeding means, vertically disposed fixed walls, and rotatable wall members extending above and below the grate level and driven from said fuel feeding means, to change the relations of the parts of the fire face of each 75 member with respect to the grate.

In testimony, that I claim the foregoing as my invention, I have signed my name this 1st day of May 1922.

JOHN J. ENGLISH.
